CAP

Leo V. Goodman and Thomas Neal,
Indianapolis, Ind.

Application September 2, 1950, Serial No. 12,048

Term of patent 3½ years

(Cl. D3—13)

To all whom it may concern:

Be it known that we, Leo V. Goodman and Thomas Neal, citizens of the United States, residing at Indianapolis, in the county of Marion and State of Indiana, have invented a new, original, and ornamental Design for a Cap, of which the following is a specification, reference being had to the accompanying drawing, forming part thereof.

In the drawings,

Fig. 1 is a top plan view of a cap, showing our new design, the flag and staff on the top thereof being omitted for convenience of illustration,

Fig. 2 is a side perspective view, and

Fig. 3 is another perspective view thereof.

We claim:

The ornamental design for a cap, as shown and described.

LEO V. GOODMAN.
THOMAS NEAL.
